UNITED STATES PATENT OFFICE.

EDWIN C. FISHER, OF CLAREMONT, NEW HAMPSHIRE.

CAMERA-STAND.

SPECIFICATION forming part of Letters Patent No. 423,551, dated March 18, 1890.

Application filed October 14, 1889. Serial No. 326,905. (No model.)

To all whom it may concern:

Be it known that I, EDWIN C. FISHER, a resident of Claremont, in the county of Sullivan and State of New Hampshire, have invented 5 certain new and useful Improvements in Camera-Stands; and I do hereby declare the following to be a full, clear, and exact description of the invention, such as will enable others skilled in the art to which it pertains to 10 make and use the same.

The object of the invention is to improve the efficiency of camera-stands; and the invention consists in the construction herein-after described and pointed out.

15 In the accompanying drawings, Figure 1 is a front elevation, partly in section. Fig. 2 is a side elevation. Fig. 3 is a top plan of the base and standards. Fig. 4 is a horizontal section, on an enlarged scale, of the camera-table, on the line X X of Fig. 1. Fig. 5 is an enlarged side elevation, partly in section, of the camera-table; and Fig. 6 is a horizontal section, on an enlarged scale, of the same on line Y Y of Fig. 1.

25 The two standards A A' are bolted securely to posts or bracket-arms of the iron base B B', and are provided with interiorly-placed T-shaped grooves D D', to receive the correspondingly-shaped nuts G G', which are connected by means of the rods F F', secured eccentrically to the rotating plate E. This plate has a journal E' in the side wall of the table C. Said plate is adapted to be turned by a lever E², to draw the nuts and consequently 30 the standards A A' toward each other, by which means they may be made to press against the table C with a greater or less force, as desired.

A wire, cord, or strap is indicated by H H', 40 the ends of which are secured near the top of the grooves D, the body of the wire or rope being extended down in the grooves and about pulleys I I' and spring-drum J, which are journaled in the ends of table C. L indicates 45 a tilting board supported on the table and adjusted by the hand-screw M, which passes through the top of the table. The base is provided with rubber-covered casters K.

N indicates a catch, engaging the flattened 50 end of the axis of the spring-drum, it being shown engaged by full lines in Fig. 5 and dis-

engaged by dotted lines. It is disengaged whenever it is desired to vary the tension of the spring in the drum.

When the table C is raised, the nuts G G' 55 slide in the grooves, eccentric-plate E having been turned to take off friction, and the rope is wound upon the drum by its spring.

Any well-known means of counterbalancing may be substituted without departing from 60 the invention.

The distance apart of the standards, which are preferably made of elastic material—such as wood—may be regulated by the eccentric E, in the manner above explained, to increase 65 or diminish the friction of the table with said standards.

By the use of the rods F F' and the nuts I am enabled to dispense with a cross-beam above the table, which beam would interfere 70 to some extent with the elevation of the table and would render necessary higher standards than required by the present construction to secure the same elevation of the camera, and as there is no obstruction between my camera-table and the low base, it is obvious that a 75 wide range of position in a vertical direction is secured without any unnecessary height of the stand.

It is not essential that the grooves be made 80 of T form in cross-section, as any equivalent shape may be substituted, the nuts being correspondingly altered. Thus, for example, an L-shaped groove could be employed and rings or grooves might be formed on or in the ends 85 of the levers and made to embrace the standards or suitable projections thereon without sacrificing all the advantages of my improvement. The so-called "nuts" may also be formed integral with the rods by casting or otherwise, and other details can be varied by mechanical skill, as will be understood. For example, instead of the plate having the rods attached eccentrically, a well-known form of nut having its interior oppositely screw-threaded at its ends and adapted to engage corresponding screw-thread on the rods F F' might be employed for adjusting said rods.

Having thus described my invention, what I desire to secure by Letters Patent is—

1. The camera-stand consisting of the base B B', provided with rubber-covered casters,

the grooved standards A A', bolted to posts fixed on the base, the table C, and the connecting-rods, and nuts, substantially as set forth.

5. 2. The combination, in a camera-stand, of the grooved standards, the table, the connecting-rods, and nuts, substantially as described.

3. The combination, in a camera-stand, of the grooved standards, the table, the connecting-rods and nuts, and means of adjusting the rods to slightly vary the distance of the standards, substantially as described.

4. The combination, with the standards having vertical grooves, and the table, of the cords lying in the grooves, the pulleys, and the spring-drum, substantially as set forth.

In testimony whereof I have signed this specification in the presence of two subscribing witnesses.

EDWIN C. FISHER.
